UNITED STATES PATENT OFFICE.

ROBERT VOM CLEFF, JR., OF JERSEY CITY, NEW JERSEY, AND CHARLES F. BENEDICT, OF BROOKLYN, NEW YORK.

MATCH-BOX.

No. 861,265.

Specification of Letters Patent.

Patented July 30, 1907.

Application filed October 16, 1906. Serial No. 339,175.

To all whom it may concern:

Be it known that we, ROBERT VOM CLEFF, Jr., a citizen of the United States of America, residing at Jersey City, in the county of Hudson and State of New Jersey, and CHARLES F. BENEDICT, a citizen of the United States of America, residing at Brooklyn, in the county of Kings and State of New York, have invented certain new and useful Improvements in Match-Boxes, of which the following is a specification.

10 This invention has reference to improvements in match boxes or match safes.

It pertains particularly to a novel match box whose mechanism, when operated, brings into view a single burning match which has ignited itself while passing 15 out of the box and is retained partly within same until released so that it can not fall out and damage, for instance, carpets and the like.

The invention is illustrated in the accompanying drawing in which:

20 Figure 1 represents in front elevation a match box which embodies in desirable form the present improvements. Fig. 2 is a view of same in side elevation. Fig. 3 shows same in top plan view. Fig. 4 is a view in vertical section on an enlarged scale showing the match 25 box ready to be operated. Fig. 5 is a like sectional view showing the match box after it has been operated. Fig. 6 is a view in section on line 6, 6 of Fig. 4, and Fig. 7 is a sectional view on line 7, 7 of Fig. 5.

Similar characters of reference denote like parts in 30 all the figures.

The novel match box is preferably made of metal. Either cheap or expensive material may be used and the box ornamented and engraved in accordance with the wants of the public. The device may be operated 35 by one hand which is sometimes of great convenience.

On the drawing *a* represents the box whose bottom *b* is secured by a hinge *c* so that the matches may be introduced into the box from below. The top portion of the box is provided with an interior partition *d* which

40 has an opening *e* near its left hand end as shown in Figs. 4 and 5. An opening *f* is provided in the top *g* of the box, it coincides with the opening *e*. The space between the top *g* and the partition *d* contains a spring actuated igniter which consists of the igniter proper *i* and the spring *s*.

45 The igniter has a rough bottom surface *i*¹ and a small downward extension *i*² forming a catch shoulder which is flush with the rough surface and rests against the wall *a*¹ of the box *a* while the reduced top portion of the igniter passes through an opening *h* in the top portion of the said side *a*¹ of the box *a*.

50 A spring *k* is secured to the top of the igniter which keeps same normally in a locked condition and slides along the bottom surface of the top *g* of the box when the device is operated. The igniter has an opening *l* which coincides with the openings *e*, *f* after the device

has been operated. A heavy shoulder *n* is formed on the igniter near its opening *l* and a short rod *r* on the said shoulder. This rod acts as a support for the spring *s*. The spring *s* is cylindrical in form. At its right hand end there is a short sheet metal cover *p* which fits exactly into the space between the top *g* of the box and the partition *d* and closes the space on this side as shown in Figs. 4 and 5. A pin *p*¹ passing through the top *g* of the box *a*, the sheet metal covering *p* and the partition *d* holds the spring *s* in position. There is 60 further a stop pin *q* which arrests the motion of the igniter when same has been actuated by the spring *s*, it is in such a location that the opening *l* in the igniter coincides with the openings *e*, *f* when the shoulder *n* rests against it.

70 Within the box there is provided a device *t* which normally separates the matches from the operative mechanism located within the box near the wall *a*¹ of same. This device we prefer to call the deflector, its shape is apparent from Fig. 7. Its left side forms a 75 right angle with the side *a*² of the box while its right side is slanting and forms an acute angle with the said side *a*². As shown in Fig. 7 the deflector leaves a free space between its top and the side *a*³ of the box. The side *a*¹ of the box is provided with a slot *u* shown in 80 Figs. 4 and 5. A match ejector *v* is movably mounted to the left of the deflector *t*, it rests against the wall *a*¹ and has a push knob *v*¹ which extends through the slot *u*. At the bottom the ejector forms a foot *v*² on the top surface of which rests the bottom end of the match to 85 be ejected. A match guiding device *w* is secured within the box between the deflector and the wall *a*¹. This guide carries a spring *x* which is made of sheet steel and extends vertically up and then horizontally over so that its portion *x*¹ is between the partition *d* and 90 the top end of the deflector *t*. This spring has an opening *y* which normally coincides with the openings in the partition and the top of the box. Said openings thus form a continuous open passage for the match except that the spring *x* is so mounted that its opening 95 *y* is slightly to the left in relation to the opening *e*. The match when moving upward rubs against this surface until the push button *v*¹ reaches the spring *x*. Thus the match is prevented from jumping out of the box. Should it be desirable for any reason to return 100 the match into the box the block *x*² of the spring is slightly pushed in whereby the opening *y* is brought into such a position as to allow the match to drop back into the guide.

The device is operated substantially in the following 105 manner:—By slightly shaking the box a match is made to pass over the deflector down into the match guide *w* while its bottom end rests on the foot of the ejector *v*. The space between the match guide *w* and the rectangular side of the deflector *t* is such that but one match 110

has room there. Now the box is held by the fingers on its top right-hand portion and the thumb placed against the push knob v^1 moving it upward. This carries the match through the openings y and e . Soon the head 5 of the match will strike against the rough surface i^1 of the igniter whereby same is moved upward. At a certain moment the force of the spring k has been overcome and the extension i^2 of the igniter is released from the side a^1 of the box. Immediately the spring 10 s enters into action whereby the igniter is partly moved out of the box as illustrated in Fig. 5. The rough surface i^1 passes along the inflammable head of the match and lights same. When the shoulder n rests against the stop pin q the opening l is in line with the other 15 openings and the match shoots out through the said opening l and the opening f in the top of the box. Meanwhile the push knob v^1 has reached the flat spring x and moves same somewhat inwardly whereby the surface x^2 of said spring is made to bind against the 20 match and hold same in position. After the match has been used the ejector is moved downward whereby the spring x is released from the match and same may be shaken out of the box when the block x^3 is slightly pushed in, or it may be taken out with the fingers. 25 After this the igniter is pushed back into the box when same will be again ready for operation.

Having thus described our invention we claim as new and desire to secure by Letters Patent:

1. A match box adapted to bring into view part of a 30 burning match during one operation comprising, a match receptacle having a slotted side wall with an opening near its upper end and an opening in its top near said slotted side wall, a partition in the upper part of the box having an opening which coincides with the top opening, a spring 35 actuated igniter mounted between the top of the box and

the partition and extending slightly through the opening in the slotted side wall forming there a shoulder which normally rests against said wall and having a central opening coinciding with the openings in the top and partition upon release of the igniter, a flat spring secured to the top 40 of the igniter near the top opening, and a stop pin arresting the released igniter, and means for moving a match upward whereby the igniter is released and the device operated.

2. In a match box of the type described, a spring actuated igniter of elongated shape comprising a shouldered middle portion, a rod extending therefrom in one direction, and an igniter portion extending in a direction opposite to said rod, said igniter portion having a catch shoulder near 45 its end, a roughened bottom and an opening near the middle portion, a cylindrical spring surrounding the rod, a flat spring secured to the top of the igniter portion, and a match ejecting means arranged in ejecting a match to operate said igniter.

3. In a match box of the type described, a match receptacle having a slotted side wall with an opening near its upper end and an opening in its top near said slotted side wall, a partition in the upper part of the box having an opening which coincides with the top opening, a spring actuated match igniter located in the receptacle between the 50 partition and the top, a match guide located within the box, a flat spring secured to the upper portion of said guide extending upward and then horizontally over and having an opening in its horizontal portion coinciding with the openings in the partition and top of the box and slightly 55 to one side relative to the upward moving match, a block secured to the outer side of the spring, and means in the slotted side wall to move the match upward and the spring towards the match guide whereby the match is held in position until released.

Signed at New York, N. Y. this 15th day of October, 1906.
